UNITED STATES PATENT OFFICE.

JAMES STONE, OF LA CROSSE, WISCONSIN.

COLLAPSIBLE TABLE.

1,272,560.

Specification of Letters Patent. Patented July 16, 1918.

Application filed October 7, 1915. Serial No. 54,481.

To all whom it may concern:

Be it known that I, JAMES STONE, a citizen of the United States, and a resident of La Crosse, in the county of La Crosse and State of Wisconsin, have invented certain new and useful Improvements in Collapsible Tables; and I do hereby declare that the following is a full, clear, and exact description thereof, reference being had to the accompanying drawings, and to the letters of reference marked thereon, which form a part of this specification.

This invention relates to a collapsible table, more particularly designed for use by automobilists, campers, picnickers, card players, and the like, and which table, when not in use, may be rolled or folded up into a small compass, so that it may be placed in a suit-case or other suitable receptacle for transportation, and when set up and in use its flexible top will be held smooth, flat, and rigid.

A table embodying the features of my invention is provided with a flexible top made from a layer or layers of fabric or the like, so that the table may be rolled or folded up into a small compass or compact article when not in use. The several legs of the table are secured to the under side thereof, in such a manner that said legs may be folded inward against the under side of the table top, and be completely enveloped in the latter, when the table is rolled or folded up. I also provide foldable braces adapted to hold the flexible top thereof rigid, flat, and smooth, when the table is set up and in use.

The invention consists further in the matters hereinafter described and more particularly pointed out in the appended claims.

In the accompanying drawings—

Figure 1 is a perspective view of a collapsible table constructed in accordance with my invention, said table being shown set up and ready for use;

Fig. 2 is an enlarged bottom plan view of the parts shown in Fig. 1;

Fig. 3 is a transverse sectional view taken on line 3—3 of Fig. 1;

Fig. 4 is a fragmentary view taken on line 4—4 of Fig. 3;

Fig. 5 is a bottom plan view of the parts

shown in Fig. 4, with the exception that the table leg is shown in the position it occupies after being folded inward against the under side of the table;

Fig. 6 is a fragmentary longitudinal sectional view taken on line 6—6 of Fig. 5, and with parts in elevation;

Fig. 7 is a fragmentary side view of the table and showing one of the side brace members in its extended position;

Fig. 8 is a bottom plan view of the parts shown in Fig. 7;

Fig. 9 is a fragmentary perspective view of two of the legs at one end of the table, and showing the brace bar extending therebetween;

Fig. 10 is a fragmentary perspective view of the table shown in Fig. 1 folded or rolled up into a compact form and ready for transportation or storage;

Fig. 11 is a longitudinal sectional view of a table having a flexible top made of two layers of fabric secured together at intervals to form a series of parallel pockets in which are inserted stiffening strips;

Fig. 12 is a side elevational view of a set up table embodying the features of my invention but differing slightly as to details of construction from the table shown in the preceding figures of the drawings;

Fig. 13 is an end elevational view of the table shown in Fig. 12;

Figs. 14 and 15 are transverse sectional views taken on lines 14—14 and 15—15, respectively, of Fig. 12;

Figs. 16 and 17 are fragmentary sectional views taken on lines 16—16 and 17—17, respectively, of Fig. 19;

Fig. 18 is a view of a detail of construction taken on line 18—18 of Fig. 12;

Fig. 19 is a longitudinal sectional view with parts in elevation and taken on the indirect line 19—19 of Fig. 12; and

Fig. 20 is a perspective view of the plate of the latch device to be herein described.

In the accompanying drawings, I have shown in detail a collapsible table 15 constructed in accordance with my invention, and, as illustrated, said table comprises a flexible top 16, preferably rectangular in form, and to the under side of which are attached several legs 17, 18, the latter serv-

ing to support the table when unfolded and set up. The table legs are arranged in sets with two legs 17, 18 in each set. One set of legs is located at each end of the table, 5 and another set of legs is located intermediate the ends of the table. The legs of the set at each end of the table are located at the corners of the table. As more clearly shown in Figs. 1 and 2, one leg 17, 18 of 10 the intermediate set is located at each side of the table and in substantial alinement with each other. Each leg 17, 18 is connected with the under side of the top 16 in such a manner that all of the legs may be 15 folded inward against the under side of the table and thereby permit the latter to be folded or rolled up into a small compass with all of the legs located wholly within the folded article. When it is desired to 20 use the table, the flexible top 16 is unfolded and the several legs 17, 18 moved or swung outward into an upright position, so as to support the table when the latter is set up.

As shown in Figs. 1 and 2, there are three 25 sets of legs with a pair of legs 17, 18 in each set, and the flexible top 16 is made rectangular in shape, so that the table may be folded or rolled up endwise and be no longer, when folded into a compact article, than the extreme width of its top. Secured in any suitable manner to the under side of said flexible top 16 are three flat, relatively narrow base strips or members 19, 19, 19. As illustrated, there is a base member 19 at each end of 30 the table and a base member intermediate the ends of the table and to which the intermediate legs 17, 18 are secured. Each base member 19 extends fully across the table, and said base members are arranged 35 parallel to the ends of said table. Each base member 19 is no greater in length than the width of the table. One set of legs 17, 18 is attached to each of said base members 19, 19, there being one leg on each end of said 40 base member. The inner end of each leg 17, 18 is squared, so that the leg will abut endwise against the outer flat face of its associated base member 19, when said leg is in its upright and table-supporting position. 45 (See Fig. 3.) Each table leg 17, 18 is connected with its associated base member 19 by means of a hinge 20, the two parts 21, 22 of which overlap and are located between the table leg and its associated base member 50 19, when said leg is folded inward against the under side of the table. (See Fig. 6.) The part 22 of said hinge is countersunk in and secured flatwise against the inner face of said table leg by means of screws or like 55 fastening members 23, 23, and the other part 21 of said hinge is secured flatwise in a like recess in the outer face of said base member 19 by screws or the like 24, 24. The pintle 60 25 of said hinge is so arranged that the

hinge breaks inward and permits the table 65 leg to be swung inward against its associated base member 19. Each leg 17, 18 is secured to its base member 19 by a hinge 20, as described, and each leg is equal in length but is no greater in length than the width of 70 the table. Manifestly, when the table is collapsed and folded up into a compact article, its legs do not extend beyond the ends of the folded table.

In order to hold each leg 17, 18 in its upright position, when the table is unfolded and set up, so that said leg may not be accidentally folded inward against the under side of the table, I provide the following construction: For each table leg I provide a 75 brace rod 26 having pivoted or hinged connection with the leg at one end and sliding connection with the under side of the table at the other end. The sliding end of said brace rod 26 is adapted to enter a suitable 80 locking notch or recess formed in a part of the base member 19, so that, when the leg reaches its upright position and the sliding end of said brace rod 26 engages said locking notch, the brace rod 26 serves to 85 hold the leg upright and prevents said leg from being accidentally moved inward. As illustrated in Figs. 4 and 5, said brace rod 26 has its inner end bent laterally to provide a hook-like part 27 adapted to extend 90 into a slot or groove 28 formed in a guide member 29, the latter being secured to said base member 19 in alinement with said table leg 17. When said leg 17 is moved from its 95 folded position into its upright position, the brace rod 26 is drawn outward, and its hooked end 27 is moved from the inner to the forward end of said slot 28. At the forward end of the latter is provided a locking recess or socket 30, into which the hooked 100 end of the brace member 26 snaps or moves, when the table leg 17 reaches its upright position. In said Fig. 4, I have shown the table leg 17 in its upright position and the hooked end of said brace rod 26 in said recess 30. In such position of the parts, the 105 brace rod 26 serves to hold the table leg 17 upright and prevents the same from being accidentally moved inward. Said brace rod 26 is made of spring metal, and its normal 110 tendency is to snap into said recess 30. To move the leg 17 from its upright position inward and against the under side of the table, the hooked end 27 of said brace rod 26 is manually withdrawn from said recess 30, 115 whereupon the leg may be moved inward against the member 19. To prevent the hooked end 27 of said brace rod 26 from being moved laterally out of the slot 28, I provide a guard strip 31 arranged parallel 120 to said guide-member 29 and secured to said base member 19 opposite said slot 28. As 125 shown in Fig. 4, said guide-member 29 and

guard strip 31 are secured to said base member 19 by screws or other fastening members 32, 33, respectively. The distance between the guide-member 29 and its guard strip 31 is just sufficient to allow the hooked end of the brace rod 26 to slide freely endwise therebetween. As each table leg 17, 18 is provided with a brace rod 26, there is a guide-member 29 and guard strip 31 for each brace rod.

Inasmuch as each guide-member 29 and guard strip 31 are secured to the base member 19 in alinement with its associated table leg 17, 18, and each table leg is adapted to fold inward on its base member, each table leg is provided with a slot 34 intermediate its ends to receive said guide-member 29. The guard strip 31 is not as thick as its guide-member 29, and the table leg is provided in its inner face with a recess 35 to receive said guard strip. (See Fig. 6.) As illustrated in Figs. 4 and 5, the outer end 36 of said brace rod 26 is bent laterally from the body of said rod and is inserted through the eye of a screw-eye 37 secured to said leg in said slot 34. The extreme outer end of said brace rod 26 is upset or headed, so that said brace rod will not become disengaged from said screw-eye 37. As shown in the drawings, said screw-eye 37 is secured to said leg at the inner end of its slot 34, and when the table leg is folded inward against the base member 19, the parts occupy the positions shown in Fig. 5.

When the table 15 is set up for use, as shown in Fig. 1, I provide means for bracing the same longitudinally, so that the flexible top 16 will be held rigid, flat, and smooth. Such bracing means comprises a plurality of brace bars 38, 38 arranged to extend lengthwise of the table along its side edges and between each pair of legs 17, 18 along each side of the table. As all of the brace bars employed are alike in construction, I will describe only one of the same in detail. Each brace bar 38 is made and arranged as best shown in Figs. 7 and 8. As illustrated, the brace bar 38 is of a length to extend between two legs 17, 17 and abuts endwise against the opposed side faces of said legs. Said brace bar 38 is preferably made of metal and in two sections 39, 40, said sections being connected at their meeting ends by a hinge 41. Said hinge 41 is so constructed and arranged that the sections of the brace bar may be folded or swung back one upon the other toward one of the legs 17, 17, but prevented from being moved out of alinement when fully extended, as shown in full lines in Figs. 7 and 8. One end of said brace bar 38 has flexible connection with one of the legs 17, between which it ends, and, as shown, such flexible connection is made by means of a hinge 42. One part

43 of said hinge 42 is secured flatwise against one side face of a leg 17 by screws or other fastening members 44, 44. The other part 45 is countersunk in the section 40 of said brace bar and is secured flatwise thereto by screws or the like 46, 46. Said hinge 42 permits said brace bar 38 to be swung into a position extending along side of the leg 17 to which said brace bar is attached, and when alongside of said leg said brace bar will be carried with said leg, when the latter is moved inward against the under side of the table. (See Fig. 5.) When the leg 17 is swung into its upright position, the brace bar 38 is carried therewith, and said brace bar may then swing into position extending between the two legs 17, 17 as shown in Figs. 7 and 8. To hold said brace bar 38 in its extended or bracing position and prevent the same from being accidentally moved into collapsed position alongside of the table leg to which it is hinged, I provide a detachable fastening means, as shown in said Figs. 7 and 8. As illustrated, said brace bar 38 is provided adjacent its outer end with a longitudinally extending slot 47 adapted to receive a clamp member 48 rotatably secured to said base member 19 and in a position to extend through said slot, when said brace bar 38 is extended. Said clamping member 48 is provided with a flat head, as shown, so that when the latter is turned to be parallel with the side edges of the table top 16, said head will pass through said slot 47. After the head of said clamping member 48 has passed through the slot 47, said clamping member is turned about a vertical axis so as to bring its head across said slot 47. In this position of said clamping member 48, the brace bar 38 is held extended and in bracing position. The outer end of said brace bar 38 is adapted to enter a socket member 49 secured against the side face of the leg 17 opposite the leg to which the other end of said brace bar 38 is hinged. As illustrated in Figs. 7 and 8, said socket member 49 has bottom, end, and side walls, the latter holding the brace bar against lateral movement. The normal length of said brace bar 38 is slightly greater than the distance between the table legs between which said brace bar is adapted to extend. Consequently, the brace bar 38, when first moved into position to extend between two table legs, assumes the position shown in dotted lines in Fig. 7. In this position the free end of said brace bar 38 extends at an incline into said socket member 49 and contacts with the rear wall thereof. The brace bar 38 is then forced toward the table top and assumes its bracing position, as shown in full lines in said Figs. 7 and 8, and serves to maintain the portion of the table top 16 between the legs taut, flat, and smooth. The

socket member 49 is secured to said leg 17 and is carried with the leg, when the latter is moved inward against the under side of the table. As shown in Figs. 1 and 2, there are two brace bars 38, 38 on each side of the table, one brace bar extending between each corner leg and the leg located intermediate the ends of the table.

For bracing the table 15 at each end thereof, I provide the following construction: As shown in Fig. 9, a flat strip 50, preferably made of metal, is pivoted at one end thereof by a pin 51 to the outer side of and adjacent the hinged end of the leg 17 at the corner of said table. Said end brace 50 is substantially as long as the width of the table and is adapted to extend between the legs 17, 18 at the ends thereof. The free end of said end brace 50 is bent inward to provide a flange 52. The opposite leg 18 is provided at its hinged end with a laterally extending flange 53. When the end brace 50 extends across the end of said table, as shown in Fig. 9, the flange 52 of said end brace is located behind and bears flatwise against the flange 53. Said flanges 52, 53 are prevented from moving laterally and endwise apart by a headed lug 54 on said flange 53 extending inwardly through a slot 55 in said flange 52. Said end brace 50 when in bracing position bears edgewise against the base member 19 and is held in such position by a headed clamp member 56 rotatably secured to the base member 19. Said clamp member 56 is adapted to extend through a slot 57 formed in an inwardly extending lug 58 made a part of said end brace 50. When the end legs 17, 18 of the table are to be folded inward against the under side of the table, the clamp member 56 is turned about its vertical axis, so that its enlarged head may pass through the slot 58, and then said end brace 50 may be swung alongside of the leg 17 to which it is pivotally connected. The leg 18 is then moved inward against the base member 19 and the flange 52 carried therewith. The base member 19 is provided with a recess 59 adapted to receive the headed lug 54 and thereby enable said leg 18 to bear flatwise throughout its length against its associated base member 19. After the said leg 18 has been collapsed, the opposite leg 17 is collapsed carrying therewith the end brace 50. When the parts are in this position, the end legs 17, 18 are folded alongside one another with the guide-members 29, 29 for each leg in the slots 34, 34 formed in said legs. For the sake of clearness of illustration, the guide-members 29, 29 and guard strips 31, 31 for each end leg 17, 18 are not shown in Fig. 9. As shown in dotted lines in Fig. 9, the end brace 50 is longer than the table leg 17 to which said end brace is secured, and when

said end brace is moved into a position 65 alongside of said leg 17, the end flange 52 of said end brace extends inward over the outer end of said leg. The slot 34 in the leg 17 is made long enough to receive the headed clamp member 56 when said leg is collapsed. As shown in Figs. 1 and 2, there is an end brace 50 at each end of the table, and each end brace extends across the table beneath the same.

In order to prevent each side brace bar 75 38, 38 from moving away from its associated table leg, when the parts are folded, I provide on each table leg a clamp member 61 adapted to enter the slot 47 in said brace bar. (See Fig. 5.)

The table 15 above described and shown in Figs. 1 to 9 both inclusive is set up in the following manner. After the flexible table top 16 has been unfolded, the legs 17, 18 are moved into their upright positions and 85 braced by the brace rods 26, 26. The several side brace bars 38, 38 are then moved into distended positions and locked to the table by the clamp members 48, 48. The end braces 50, 50 are then moved into positions to extend across and beneath the table at the ends thereof and locked in bracing position by the clamp members 56, 56. When the parts are thus positioned, the table is set up on its legs 17, 18, as shown in Fig. 1. 95 To collapse the table 15, the end and side braces are unlocked and moved into position alongside of the legs to which such braces are connected; then the brace rods 26, 26 are manually moved laterally so as to disengage 100 their locked ends 27, 27 from the recesses 30, 30 and the legs moved inward against the base members 19, 19. When the parts are thus positioned, the flexible table top 16 is rolled up so as to bring the base members 105 19, 19 and connected legs 17, 18 within the folds of the top 16 and one upon the other, as shown in Fig. 10. When so folded the table may be placed in a suit-case or other receptacle provided for that purpose. 110

In order that the table 15 may be easily folded up into a small compass, as shown in Fig. 10, the section of the flexible top between one end base member 19 and the intermediate base member 19 is made longer 115 than the section of said flexible top between said intermediate base member 19 and the other end base member 19, as shown in Fig. 1. This permits the several base members 19, 19 to be superposed, when said table is 120 rolled or folded up.

In Fig. 11, I have shown the flexible table top 16 made of two layers of material 62, 63, such as fabric, oilcloth, leather, or the like. Said layers 62, 63 are joined to each 125 other at intervals by means of transversely extending parallel lines of stitching 64, to form a plurality of transversely extending

parallel pockets in which are inserted stiffening strips 65, 65. Said stiffening strips may be made of any suitable material, but for lightness in weight preferably consist of 5 wood or fiber-board. The layers 62, 63 are of such length with respect to each other that the upper layer will be flat and smooth when the table is distended and in use. When the table is rolled up, the lower layer 10 63 will of course be inward. As shown in said Fig. 11, the pockets are provided only in the sections of the flexible top between the base mebers 19, 19.

Whether the table top 16 is made of a 15 single layer of material, as shown in Figs. 1 and 2, or of a double and pocketed layer, as shown in Fig. 11, the table top is flexible and may be readily rolled up. As illustrated in Fig. 11, said pockets and stiffening strips 20 65, 65 extend across the table, so that the latter may be rolled up endwise.

As an additional means of bracing the table top 16 shown in Fig. 2, when the same is extended and in use, I provide brace 25 members 66, 66 centrally disposed and arranged to extend lengthwise of the table. As illustrated, there are two brace members 66, 66, one extending from each end base member 19, 19 to the intermediate base 30 member 19. Each brace member 66 is preferably made of sheet metal and has detachable connection at its ends with the associated base members 19, 19, so that said brace members 66, 66 may be removed when the 35 table is to be collapsed and folded or rolled up. The form of detachable connection shown in the drawings is made as follows: Each brace member 66 is provided adjacent each end with a slot 67 opening through the 40 side edge of the brace member. Said slots 67, 67 open on opposite sides of the brace member and are adapted to receive headed studs 68, 68 on said base members 19, 19. When the table top 16 is to be folded or 45 rolled up, said brace members 66, 66 are removed and placed on the folded legs, so that said brace members will be enveloped within the folded article.

In Figs. 12 to 20 both inclusive of the accompanying drawings, I have shown a 50 collapsible table embodying the features of my invention, but differing somewhat as to details of construction from the table 15 shown in the preceding figures of the drawings. As 55 illustrated in Figs. 12 and 13, the table 70 comprises a flexible top 71, preferably rectangular in form and similar to the flexible top 16 of the table 15 shown in Figs. 1 to 3. To the under side of said flexible top 71 are 60 secured base members 72, 72, 72, the latter being the same in construction and arranged similarly to the base members 19, 19, 19 shown in said Figs. 1 to 3. Said table 70 is provided with supporting legs 73, 73,

73 hingedly secured to the base members 72, 65 72 in the same manner as the legs 17, 18 shown in Figs. 1, 2 and 3. In order to hold each leg 73, 73 in its upright or table-supporting position, when the table 70 is unfolded and set up, so that said legs may not 70 be accidentally collapsed or moved inward against the under side of the table, I provide the following construction. For each leg 73 I provide a brace rod 74, the latter having 75 pivotal connection at one end with its associated base member 72 and sliding connection at the other end with its associated table leg 73. As the bracing means for each leg 73 is the same in construction and operation, a description of one, it is thought, will suffice for all. As shown in Fig. 13, a swivel block 75 is secured, by means of fastening members preferably in the form of screw bolts 76, 76, to the under side of each base member 72. There is a swivel block 75 for 80 each table leg 73, 73, and each swivel block is secured to the base member 72 adjacent the end to which the table leg is hinged. One end of the brace rod 74 is bent laterally from the body of the rod, and the bent end 85 of the rod is inserted in a suitable aperture provided in the swivel block 75. The other end 77 of said brace rod 74 is bent laterally from the body of the rod, and such hook-shaped end 77 is adapted to slide endwise in 90 a slot 78 formed in said table leg 73. The latter being hinged to the base member 72, said leg may be swung inward against the under side of the table and contact flatwise throughout its length against the base member to which it is hinged. Said slot 78 is made long enough to receive said swivel block 75. Located in said slot 78 and extending lengthwise thereof is a guide member 95 79, the latter being provided with an outwardly opening, longitudinal channel or slide-way 80, in which slides the bent end 77 of the brace rod 74, when the leg 73 is swung inward into its collapsed position or outward into its upright or table-supporting 100 position. In order to lock the rod 74 in both of its extreme positions and prevent the leg 73 from being accidentally swung inward, when said leg is in its upright or table-supporting position, and further prevent 115 said leg from accidentally swinging outward when in its collapsed position, I provide adjacent each of said guide members 79 a transversely arranged locking notch or aperture 81, 81, into which the bent end 77 of the rod 74 snaps, when the latter reaches said locking aperture. As shown in Fig. 13, the bent end 77 of the brace rod 74 extends 120 into the uppermost locking aperture 81, and the rod 74 serves to hold the leg 73 in its upright or table-supporting position. When the leg 73 is collapsed, the bent end 77 of the rod extends into the other locking aperture 125

81, and thereby holds said leg in its collapsed position. To disengage the end 77 of the rod 74 from either locking aperture 81, the free end of said rod is sprung laterally so as to withdraw its bent end 77 from the locking aperture. This being accomplished, the table leg 73 may be moved or swung freely inward or outward, depending on which is desired. As best shown in Fig. 14, 10 the guide member 79 is provided with marginal lugs 82, 82 adapted to embrace the sides of the table leg, and fastening members in the form of screws 83 are inserted through said lugs 82 and into the leg 73.

15 In order to hold the flexible top 71 distended, rigid, flat, and smooth, when the table 70 is set up and in use, as shown in Figs. 12 and 13, I provide bracing means of the following construction, and such bracing means accomplishes the same purpose as the brace members 38, 38 hereinbefore described and shown in connection with the table 15 illustrated in Figs. 1 to 10 of the drawings. As shown in Figs. 12 and 13, the bracing means employed with the table 70 comprises brace bars 84, 85 arranged in pairs and with a pair of such brace bars at each side of the table. The pair of brace bars 84, 85 at each side of the table 70 extend substantially the full length of the table, when said bars are placed in bracing position. As the pair of brace bars 84, 85 along one side of the table are constructed and used in the same manner as the pair of brace bars on the opposite side of the table, a description of one set of such brace bars at one side of the table will suffice for all. As illustrated in Figs. 12 and 19, the brace bar 84 is pivotally secured at one of its ends 20 by a pivot pin 86 to the adjacent leg 73 at the corresponding end of the table. The other brace bar 85 is pivotally secured at one of its ends by a pivot pin 87 to the leg 73 at the opposite end of the table. Each 25 brace bar 84, 85 is made of a length to extend past the centrally disposed leg 73, when said brace bars are swung into a position extending lengthwise of the table. When in such position, the free ends of said brace bars overlap each other for that portion of their lengths extending past the centrally disposed table leg 73. (See Figs. 12 and 19.) In order to hold said brace bars in their 30 bracing positions, I provide latch devices of the following description: Each latch device comprises a metal plate or like member 88, the latter being provided with a base or body portion 89 and an integral marginal flange 90. As shown in Figs. 12 and 19, there is a plate 88 secured to each base member 72, 72. The plate 88 attached to the base member 72 at the pivoted end of the brace bar 84 is applied against the inner longitudinal margin of said base member with its 35 base flange 88 secured to the under side of

the base member by suitable fastening members, and its marginal flange 90 secured by fastening screws 91 to the inner longitudinal margin of said base member. (See Fig. 16.) The base flange 89 is provided at its outer end with a lug 92 adapted to engage over the upper edge of the brace bar 84, when the table is set up and the brace bars are extended. Said latch device includes a latch member 93, the latter being in the form shown in the drawings and pivotally secured at one end by a pivot pin 94 to the flange 89. The free or swinging end of said latch member 93 is made hook-shaped, and such end is adapted to engage beneath its associated brace bar 84, 85, when the table is set up and the brace bars are swung into their bracing positions. As shown in Fig. 12, there is a latch device applied to each side of the centrally disposed base member 72, and each latch member 93, 93 of such latch devices engages beneath the overlapped portions of the brace bars 84, 85, when the table is set up and said brace bars are in their bracing positions. Fig. 17 shows one of the latch devices applied to the centrally disposed base member 72, and it will be noted that the latch member 93 has its pivot pin 94 spaced inwardly from the lug 92 a sufficient distance to allow the hook-shaped end of said latch member to engage beneath both of the overlapped portions of the brace bars. As shown in said Fig. 17, the lug 92 of each latch device applied to the centrally disposed base member 72 is adapted to engage over the upper edge of the outermost brace bar 85. When the brace bars 84, 85 are in their bracing positions, as shown in Figs. 12 and 19, the several latch devices described not only prevent the bars from being separated laterally, but also hold the bars in their distended or bracing positions. In order to prevent the brace bars 84, 85 from moving endwise toward each other, when said brace bars are in their bracing positions, and thereby hold the flexible top distended, when the table is set up, I provide on one brace bar a stop-member 96, against which the free end of the other brace bars is adapted to bear. As shown in Figs. 12, 18, and 19, said stop-member 96 is secured to the brace bar 84 by fastening members 97, 97. Said stop-member 96 is provided with an end wall or web 98 against which the free end of the brace bar 85 is adapted to abut. Said stop-member 96 is also provided with a side wall or web 99 spaced laterally from the brace bar 84 and forming therewith a recess adapted to receive the free end of said bar 85. The recess is closed at its top by a web or wall 100, which prevents the brace bar 85 from being swung, in the direction of the table top, out of longitudinal alignment with the other bar 84.

For bracing the table transversely at each end thereof, I provide an end brace member 101, such as shown in Fig. 13. Said end brace member 101 is secured on one edge 5 to the end base member 72 and extends lengthwise thereof. Said end brace member 101 is disposed midway between the longitudinal edges of said base member 72 and is interposed between the end legs 73, 73, 10 when the latter are collapsed.

In Fig. 19, I have shown the manner in which each brace bar 84, 85 is pivotally connected with its associated table leg 73, 73. As illustrated, oppositely disposed metal plates 102, 103 are applied against the sides of each end leg 73, and said plates are secured to each other and to the table by fastening members 104, 104 inserted through such parts. Said plates are located at the 15 hinged end of each table leg, and the pivot pin 86 for the brace bar 84 is in the form of a rivet extending through a bushing or sleeve 105 inserted in an aperture in said brace bar 84. The outer end of the rivet 86 is headed, and a washer 106 is interposed between the brace bar 84 and the headed end of such rivet. Said rivet 86 also extends through the plate 102 and its headed end received in a socket or recess in a portion of 20 the leg 73 behind said plate 102. The plate 102 for the pivot pin 87 is provided with an extension 107 through which the pivot pin 87 is inserted. To collapse the table 70, the latch members 93 are swung inward so as to 25 release the brace bars 84, 85 on each side of the table. Said brace bars are swung alongside of the legs 73, 73 to which they are pivoted, and all of the legs of the table 30 swung inward against the under side thereof. Thereupon the table top 71 is rolled or folded up endwise with all of the legs and brace bars within the folded article.

Those parts of the table 70 shown in Figs. 19 and 20 similar to the table parts shown 45 in the preceding figures of the drawings have been given corresponding reference characters.

The table herein described and shown in particularly useful to automobilists on outings, picnickers, campers, and the like, as the table when folded up may be easily carried as part of the outing equipment and occupy very little space therein. Furthermore, the table may be readily and easily 50 unfolded and set up and when set up efficiently serves all of the uses of a table. The many advantages of having a table which may be used on an outing and yet be collapsed and folded up into a small compact 55 or compact article capable of being easily and readily carried are apparent.

It will of course be understood that the accompanying drawings illustrate two preferred forms of collapsible table embodying 60 my invention, and that in carrying out my

invention the details of construction and arrangement of parts shown and described may be variously changed and modified without departing from the spirit and scope of my invention. I do not, therefore, desire 70 to be limited to the particular features and details of construction shown and described, except as pointed out in the appended claims.

I claim as my invention:

1. A collapsible table having a foldable 75 top substantially rectangular in shape, a supporting leg adjacent each corner of said table, said legs being pivotally secured to said top and adapted to be swung inwardly against the same, a pair of brace members 80 for holding said top distended and adapted to be extended along said top in the direction in which the same is folded up, said brace members when extended having their 85 outer ends engaged with the table and their inner ends engaged with each other, and a clamp member adapted to detachably engage at least one of said brace members for holding the same in their table supporting 90 position.

2. A collapsible table having a foldable top substantially rectangular in shape, a supporting leg adjacent each corner of said table, said legs being pivotally secured to 95 said top and adapted to be swung inwardly against the same, a pair of brace members for holding said top distended and adapted to be extended along said top in the direction in which the same is folded up, said brace members when extended having their outer 100 ends engaged with the table and their inner ends overlapping and engaged with each other, and a clamp member adapted to detachably engage the overlapped inner ends of said brace members for holding the same 105 in their table supporting position.

3. A collapsible table having a foldable top substantially rectangular in shape, a supporting leg adjacent each corner of said table, said legs being pivotally secured to 110 said top and adapted to be swung inwardly against the same, two pairs of brace members for holding said top distended and adapted to be extended one pair along each side of said top in the direction in which 115 the same is folded up, the brace members of each pair having their outer ends pivotally connected with the associated legs at the corners of the table and when extended having their inner ends overlapping and engaged with each other, and clamp members adapted to detachably engage the overlapped inner ends of said brace members for holding the same in their table supporting 120 positions.

4. A collapsible table having a foldable top substantially rectangular in shape, three supporting legs along each side of said table, one adjacent each end thereof, and the other intermediate the ends thereof, said legs be- 125 130

ing pivotally secured to the under side of said top and adapted to be swung inwardly against the same, two pairs of brace members for holding said top distended and 5 adapted to be extended one pair along each side of said top in the direction in which the same is folded up, the brace members of each pair when extended having their inner ends overlapping each other adjacent the leg intermediate the ends of said table, and a 10 clamping member adjacent each intermediate leg and adapted to engage the overlapped ends of the associated pair of brace members, for holding the latter in their 15 table-bracing positions.

5. A collapsible table having a flexible top substantially rectangular in shape and adapted to be folded up endwise, three supporting legs on each side of said table, one 20 adjacent each end thereof and the other intermediate the ends thereof, said legs being pivotally secured to the under side of said flexible top and adapted when swung inwardly against the same to extend transversely across the table, so that said table 25 when collapsed may be folded up endwise, a bracing member adapted to extend lengthwise of said table between each leg at the end of the table and the leg intermediate 30 the ends thereof, each bracing member having pivotal connection at one end with one of the legs between which it extends, a clamping member for holding each bracing member in its bracing position, and means 35 for holding each leg in its table-supporting position.

6. A table having a flexible top substantially rectangular in form, supporting legs, a pair on each side of said table, said legs 40 being pivotally secured to the under side of said flexible top and adapted, when swung inwardly against the same, to extend transversely across said table, a pair of bracing members adapted to extend between 45 each pair of legs for holding said flexible top distended when the table is set up for use, the bracing members of each pair having pivotal connection with the legs between which they extend, the bracing members of 50 each pair having their free end portions overlapping when said bracing members are extended lengthwise of the table, and clamping means for connecting the overlapping end portions of said bracing members.

55. 7. A table having a flexible top substantially rectangular in shape, base members secured to the under side of said flexible top and extending transversely across the table, there being a base member at each end of 60 the table and one intermediate the ends of the same, supporting legs, one being pivotally secured at each end of each base member and adapted to be swung inward against the same, a brace member adapted to extend 65 lengthwise of the table and between the leg

at the end of the table and the leg intermediate the ends thereof, each brace member having pivotal connection at one end with one of the legs at the end of the table, a clamping member mounted on the base 70 member intermediate the ends of the table and adapted to engage the free end of the associated brace rod, and means for holding each table leg in its table-supporting position. 75

8. A table having a flexible top substantially rectangular in shape, base members secured to the under side of said flexible top and extending transversely across the table, there being a base member at each end 80 of the table and one intermediate the ends thereof, supporting legs, one being pivotally secured at each end of each base member and adapted to be swung inward against the same, a brace member pivotally secured to each leg at each end of the table and adapted to extend between the same and the leg intermediate the ends of the table, the free ends of said brace members overlapping adjacent said intermediate legs, clamping members pivotally mounted on the intermediate base member adjacent the ends thereof and adapted to engage the overlapping ends of the associated brace members, and a brace rod for holding each leg in its 85 table-supporting position. 90

9. A table having a flexible top, base members secured to the under side of said flexible top, there being a base member at each end of the table and one extending across 100 the table between the ends thereof, supporting legs, one being pivotally secured at each end of each base member and adapted to be swung inward against the same, a brace rod for each leg and adapted to hold the same in its table-supporting position, 105 a brace member extending between each leg at the end of the table and the leg intermediate the ends thereof, each brace member having pivotal connection at one end with one of the legs between which it extends, and a clamp member adapted to engage the brace member and hold the same 110 in its bracing position.

10. A table having a flexible top, supporting legs pivotally secured thereto at each end of the table and adapted to be swung inward against said flexible top, brace bars pivoted one at each end of the table and adapted when extended lengthwise of the table to overlap each other at their free ends, and pivoted latch members adapted to engage said brace bars and hold the same 120 in their bracing positions.

11. A table having a flexible top, supporting legs pivotally secured thereto at each end of the table and adapted to be swung inward against said flexible top, a brace bar pivoted to each leg and adapted to extend lengthwise of the table; the brace bars 125 130

pivoted to the legs on one side of the table having their meeting ends overlapping when said brace bars are extended, and one of said brace bars having a part against which the other brace bar is adapted to abut.

In testimony, that I claim the foregoing as my invention, I affix my signature in the

presence of two witnesses, this 29th day of September A. D. 1915.

JAMES STONE.
